UNITED STATES PATENT OFFICE.

JESSE W. RENO, OF NEW YORK, N. Y.

APPARATUS FOR RAISING SUNKEN SHIPS.

Application filed November 25, 1919. Serial No. 340,540.

To all whom it may concern:

Be it known that I, JESSE W. RENO, a citizen of the United States, residing in New York, in the county of New York and State of New York, have invented a new and useful Improvement in Apparatus for Raising Sunken Ships, of which the following is a specification.

My invention relates to an apparatus for 10 raising sunken ships by means of shooting a number of holes in the sides of the ship by projectiles fired from a mobile gun mounted on tractor belts on the bottom of the sea; hooking hooks in the holes, the 15 hooks being attached to one end of chains, the other end of the chains being secured to open bottom air tanks or cylinders adapted to receive water and be sunk, and have the water lowered therein or expelled 20 therefrom by air admitted therein, and thus to raise the ship, by buoyant force of the cylinders.

My invention also involves an improved 25 mobile gun for shooting the holes in the sides of the ship, the gun being adapted to be lowered to the bottom of the sea, and to be supported by a tractor belt, and to be moved from one place on the bottom of the sea to another position by the tractor. 30 The work of forming the holes in the sides of the ship in my method of raising sunken ships can be conveniently and rapidly done so that any desired number of air tanks can be attached to the sunken 35 ship, and by their buoyant action raise her without strain or stress upon her structure; and in this method, ships even of very large size, and sunk in very deep water can be conveniently raised to the surface of the 40 sea. There is also a great advantage in my method of operations, because all of the permanent equipment to make the holes in the sides of the ship and the air tanks needed to raise the ship will be on or near 45 the bottom of the sea, so that in case of a storm the apparatus would be in still water, below any wave motion of the surface of the sea; in fact, virtually all of my apparatus is first lowered to the bed of the sea.

50 In carrying out my method of raising sunken ships, I attain my objects therein by the use of the apparatus illustrated in the accompanying drawings, in which—

Figure 1 is a side elevation of my mobile 55 gun, partly in vertical cross section, in

position to discharge a shot to make a hole in the desired spot in the side of the ship.

Figure 2 is a plan view of my mobile gun, partly in horizontal cross section.

Figure 3 is a side elevation of a sunken 60 ship, having a series of holes in its sides formed by my method and my buoyant air cylinders submerged and hooked to the ship, and showing a wrecking ship also.

Figure 4 is an outline end-on view of a 65 sunken ship on the bottom of the sea between my buoyant air cylinders secured to the ship by hooks in holes made in the ship by my method.

Figure 5 is a longitudinal view in section 70 of one of my buoyant air cylinders, with piping for the conduction of air, and a hook to be hooked in a hole made in the sunken ship by my method, in order to raise the 75 ship.

Figure 6 is an outline end-on view of a 80 sunken ship inclined or listed on the bottom of the sea, with one of my buoyant air cylinders and hooks made fast to her side in a hole made by my method in the art 85 of raising sunken ships.

Similar numerals refer to similar parts throughout the several views.

The mobile gun apparatus 1 comprises a 90 working air chamber, 2, let down from the surface of the sea by chains, 3, to the bottom of the sea. Air is supplied through a pipe, 4, to the chamber, under atmospheric pressure. The chamber is made strong enough to withstand the external pressure 95 due to the head of the water at the sea bottom and large enough to give the necessary working space in the interior thereof for the operators, say, for instance, two men, the dimensions being about six feet in diameter and eight feet to the ceiling or overhead. The chamber is mounted on a suitable frame or chassis, 5, movable by tractor belts, 6, adapted to be operated by a sprocket chain, 7, driven by a hand wheel, 8, located 100 in the chamber. The shaft on which the hand wheel, 8, and the sprocket chain, 7, are mounted is passed through the wall of the chamber in a conventional type of stuffing box, for instance, similar to those mentioned infra for the gun and rod. There are two tractor belts and two hand wheels, —a wheel for each belt—; in that plan or arrangement each belt is independently 105 driven by a sprocket chain and hand wheel, 110

which insures that the mobile gun apparatus can be turned around as well as propelled on the bed of the sea to any point along the sides of the ship, and the gun pointed to the 5 position where it is desired to shoot a hole in the side of the ship, 9. In the chamber I mount a gun, 10, having a bore of say, four inches, with the muzzle projected through and supported in the wall of the 10 chamber, and having an extension, 11, of the breech of the gun also projected through and supported in the wall of the chamber. The gun may be of any suitable well-known 15 type, with an approved kind of recoil mechanism, 12, or for example, I may use a type of the order say of the familiar "Davis" gun, in which the recoil of the gun is balanced so that there is no movement of the gun by recoil upon being fixed; however, if there is any recoil, and in order to allow a free backward movement of the gun, I provide stuffing boxes, 13, in the 20 walls of the chamber for both the muzzle and the extension portions of the breech of the gun. That arrangement will insure perfect balance against displacement of the gun by the external pressure of the water. The importance of this plan, whereby the gun is balanced against movement by water pressure, will be appreciated when it is reflected that at a depth of four hundred feet of water, the pressure per square inch is one hundred and seventy-two pounds; therefore, assuming that the gun will be eight 25 inches in diameter, the water pressure upon the muzzle of the gun to move the gun inwards in the chamber will be eight thousand and six hundred pounds, if unbalanced. In order to prevent the water from entering 30 the bore of the gun, I provide a valve, 14, hinged to the muzzle of the gun; the hinge of the valve is provided with a spring, which will throw the valve back after the discharge of the projectile from the gun, and the pressure of the water will thereupon keep the 35 valve tightly closed against the muzzle of the gun until it is opened by the discharge of a projectile. I purpose to use a solid steel projectile, 15, and to cause it to be projected with only sufficient energy or force 40 to do the intended work of making or forming a hole in the side of the ship, and only large enough for my purpose, but leaving the interior of the ship uninjured by the 45 projectile or shot. With the rapid-fire ammunition now in use a large number of cartridges can be carried or stored in a rack around the inner wall of the chamber so that 50 repeated trips to the surface of the sea for ammunition will not be necessary. If it be desired to make a considerable number of holes in the sides of the ship, say for instance, fifty holes, spaced apart from each other say ten feet, as rapidly as possible or 55 convenient, the working chamber can be bolted on the tractor at right angles to the tractor or to the position shown in the drawing, and the tractor be propelled on the bottom of the sea along the side of the ship, with the gun pointed in the proper direction 60 towards the side of the ship and elevated to shoot holes in the side of the ship as the gun is moved along. An indicator can be mounted on the hand wheel to indicate the number of feet the gun has been moved along the 65 side of the ship from a hole, so that the operator will know that the gun is at the desired position, say ten feet on the example given, where the next hole is to be formed and so on until all the holes desired have 70 been made, in that all of them will be spaced apart substantially the same or equal distances, if desired or at the distances desired by the operator of the mobile gun. I do not limit my invention to any particular kind of power or means to move the gun. I frame a glass window in the wall of the chamber at a proper location to enable the operators to see out of the chamber, to observe the side of the ship for instance, and to spot where the projectile is to make a hole, and see the hole when made. I have mounted in stuffing boxes in the wall of the chamber, a rod, 17, which I call an adjustment rod, and the ends of which project beyond the outside of the chamber in order to balance the external water pressure on the 75 ends of the rod. The end of the rod next to the side of the ship is bent to enable it the better to engage and direct a hook, the point of which is to enter the hole in the side of the ship. I have provided handles, 18, fixed to the rod so that the operator can move the rod in and out and turn it on its axis in the wall of the chamber. Then the point 80 of the hook is suspended opposite a hole, the rod is pushed against the hook to push the point of the hook in the hole. The function of the rod is to enable the operator to manipulate, direct or adjust the point of 85 the hook in a hole made in the side of the ship by my method. In order to direct and push the point of a hook into a hole made for it, the operator of the rod can turn the rod on its axis, so that its projected bent end 90 can be made to describe quite a large circle and reach any point therein, and the rod can be moved also out and in if necessary or desirable, to reach the hook and engage or direct or push its point into a hole and 95 hold it there until the air cylinder has risen high enough to make the chain taut that carries the hook. The hook, 19, is made fast to the end of the chain, 20, carried by the air cylinder, 21, as will be explained later 100 on, to lift the sunken ship. I will now proceed to describe my air tank and my method of attaching it to the side of the ship, and causing it to raise the sunken ship. I employ an open bottom tank or cylinder, 21. 105

It is usually towed to a position vertically over the sunken ship; whereupon an air siphon, 22, is inserted in the open bottom of the tank up through the water therein (indicated by hatched lines in Figures 3 and 5) and sufficient air is siphoned out of the tank through the conduit, 23, to permit the tank to sink gradually to the sea bed adjacent to the side of the ship. The siphon is supported by a wire rope, 24, wound on a windlass, 25, on the wrecking ship, 26, and the siphon is connected by the air conduit, 23, to an air compressor, 27, on the wrecking ship or to some other apparatus for supplying air under pressure to the air cylinders or withdrawing air therefrom as the case may be. The wire rope, 24, and winch 25, will also assist in controlling the operation of sinking the air cylinder. Made fast to the air cylinder is a chain, 20, carrying a hook, 19, on its free end, opposite the open bottom of the air cylinder. When the cylinder, chain and hook are being sunk, the hook is supported by a small wire rope, 28, which is played out from a winch (not shown) on the wrecking ship. When the air cylinder has been let down in the sea and is resting on its open bottom on the bed of the sea, the hook on the chain is manipulated by the small wire cable 28 and the adjusting rod 17 into the proper position to hook into the hole made in the side of the ship by my method for that purpose and air is then forced into the cylinder in order to cause it to rise and lift the chain with it to its full length and hold it taut and the hook in the hole, as indicated by the relative position of the cylinders shown in the Figures 3 and 4. When the cylinders by their buoyant action have raised the sunken ship and it has been towed to shallow water, and it becomes desirable to ease the strain on the hooks, or remove them, the siphon can be lowered so as to engage in a cylinder, to enable sufficient amount of air to be withdrawn therefrom to allow the cylinder to sink far enough to relieve the strain on the chain and free the hook, air is then forced into the cylinder, causing it to rise again to the surface. The air siphon will also be very useful in balancing the ship when it is almost ready to be raised from off of the bottom of the sea. For example, I have indicated a sunken ship, in Figure 6, laying on the bottom of the sea in a listed or inclined position. In such a case the air tanks, by means of my air siphon, can all be attached along the lowermost side of the ship and only sufficient air be admitted to lift that

side of the ship to cause the ship to lay on an even bottom or keel; whereupon my air tanks can be attached on both of the sides of the ship, and raise the ship from its sunken position.

Having described my invention, what I desire to secure by Letters Patent is:—

1. An apparatus adapted to be used under sea, comprising the combination of a tractor, adapted to move on the bottom of the sea, an air and water tight working chamber thereon, and means carried by the chamber for forming holes in the hull of a sunken vessel to attach thereto buoyant devices to raise the vessel.

2. An apparatus adapted to be used on the bottom of the sea, comprising the combination of a tractor, an air and water tight working chamber thereon, and a gun mounted in the chamber, adapted to fire a projectile to shoot a hole in the hull of a sunken vessel to attach thereto buoyant devices to raise the vessel.

3. An apparatus adapted to be used under sea, comprising the combination of a chamber, and a gun mounted in the chamber, the muzzle and breech of the gun projecting exteriorly of the chamber to allow the gun to recoil against the water.

4. In an apparatus adapted to be used under the sea, comprising a working chamber, a manipulating rod mounted in the walls of the said chamber, adapted to be freely moved and slid longitudinally, its opposite ends projected exteriorly of the said walls, to balance the rod against the water pressure.

5. In a diving apparatus, the combination with a tractor, of a water tight shell and a tool mounted thereon, said tool being adapted to operate upon external objects.

6. A diving apparatus comprising the combination with a tractor, a water tight shell thereon, means in the shell for forming holes in the sides of a sunken ship and means for bringing the hole-forming means to bear on any point on the sides of the sunken ships.

7. In a diving apparatus, the combination with a tractor, a water tight shell thereon, tractor belts, operable independently of each other, and means operable independently of each other to operate the belts to advance and turn the tractor, whereby the hole-forming means can be brought to bear on any point along the sides of the ships.

In testimony whereof, I have signed my name to this specification.

JESSE W. RENO.
